UNITED STATES PATENT OFFICE

154,940

DESIGN FOR A BATHROOM WALL FIXTURE

Albert W. Mayer, Tampa, Fla.

Application August 7, 1947, Serial No. 140,755

Term of patent 3½ years

(Cl. D4—3)

To all whom it may concern:

Be it known that I, Albert W. Mayer, a citizen of the United States, residing at Tampa, in the county of Hillsborough and State of Florida, have invented a new, original, and ornamental Design for a Bathroom Wall Fixture, of which the following is a specification, reference being had to the accompanying drawing, forming part thereof.

In the drawing:

I claim:

The ornamental design for a bathroom wall fixture as shown.

ALBERT W. MAYER.
